UNITED STATES PATENT OFFICE.

CHARLES L. WECHT, OF LOGANSPORT, INDIANA.

WHEELED TOY.

1,331,948.

Specification of Letters Patent. Patented Feb. 24, 1920.

Application filed March 25, 1919. Serial No. 284,928.

To all whom it may concern:

Be it known that I, CHARLES L. WECHT, citizen of the United States, residing at Logansport, in the county of Cass and State 5 of Indiana, have invented certain new and useful Improvements in Wheeled Toys, of which the following is a specification.

My present invention pertains to wheeled toys.

10 One of the objects of the invention is the provision of a toy comprising a rolling ground member or wheel and a frame member; the frame member being formed of a single piece of wire that is connected of itself to the rolling ground member and is continued at right angle to the axis of the rolling member thereby contributing at once to the cheapness of the toy and the capacity of the same to withstand rough usage.

15 Another object of the invention is the provision of a wheeled toy in which the frame member alluded to is utilized to carry a frame or figures simulating soldiers and a piece of ordnance.

20 Another object is the provision of a wheeled toy in which the wheel or rolling ground member and the frame are combined to give the toy a clacking or noise-making capacity of function.

25 Other advantageous features of the invention will be fully understood from the following description and claims when the same are read in connection with the drawings, accompanying and forming part of

30 this specification, in which:

Figure 1 is a side elevation of the toy constituting the noise-making embodiment of the invention.

Fig. 2 is a plan view of the same.

35 Fig. 3 is a detail perspective of the frame.

Fig. 4 is a side elevation of a figure-bearing embodiment.

Fig. 5 is a plan view of said embodiment.

40 Figs. 6, 7, and 8 are views of another embodiment of the invention, equipped with a carriage body for the reception of a doll or the like.

The embodiment illustrated in Figs. 1, 2 and 3, is made up of a rolling ground-member or wheel 1 that is made of any suitable material, and is provided with a central bore 2 and transverse peripheral grooves 3.

45 Combined with the ground member or wheel 1 is a frame made of a single piece 5 of wire and having a handle portion 4, a transverse journal portion 5, bail-arms 6, a

loop 8, and a rearwardly directed terminal portion 7. The journal portion 5 is disposed in the bore of the member 4, and the arms 6 reach radially from the ends of the 60 journal portion and then inwardly in a plane parallel to the axis of the member 1. Approximately in line with the transverse center of the member 1 one of the arms 6 merges into the right-angle bend 8 which, 65 in turn, merges into the handle portion 4. The other arm 6 at said point is looped, as shown in Fig. 3 to seat the rear of the handle portion 4, and the latter loop merges, in turn, into the rearwardly-directed terminal portion 7 which constitutes a support. At 70 8^a is a ratchet which is possessed of resiliency and rests under its inherent yielding pressure against the grooved periphery of the wheel or ground-member 1. From 75 this it follows that when the toy is pulled or pushed through the medium of its handle portion 4 it will produce a clacking noise calculated to excite the interest of and amuse a child. It will also be noted that 80 the wire frame is strongly connected of itself to the wheel 1 without the assistance of extraneous means which conduces materially to the cheapness of the toy.

Bent upon the wire frame of the toy and 85 thereby secured to said frame is a platform 9 which receives the terminal portion 7 of the frame and thereby is more strongly connected to the frame. The ratchet 8^a is integral with said platform 9.

At 10 is a figure formed of wood or other suitable material shaped to simulate a cannon or piece of ordnance and fixed to the handle portion of the frame. The said figure 10 lends a martial appearance to the 95 toy and is preferably, though not necessarily, employed for such reason. The rear portion of the figure 10 is disposed above and connected to the support 7.

In the embodiment shown in Figs. 4 and 100 5, the rolling ground member 1^a is in the form of a spool, and the wire frame thereof is equipped with an ordnance figure 10 and a platform 9, the latter serving to carry two soldier figures 11, one positioned at either 105 side of the piece of ordnance.

The embodiment shown in Figs. 6, 7 and 110 8 comprises a rolling ground member 1^b, a wire frame similar to those before described, a platform 9^b designed to serve as a foot rest, and a body 13 adapted to receive and carry a doll or the like, and being connected

to and supported by the rearwardly-directed terminal portion 7° of the wire frame. The rolling ground member 1^b instead of being in the form of a spool, as illustrated, may 5 consist of two disks connected by a hollow axle.

It will be apparent from the foregoing that each and every one of the embodiments 10 of my invention is possessed of the salient features ascribed to the invention; also, that each embodiment is simple, is susceptible of being quickly and easily produced without the employment of expensive machinery, is 15 sturdy and strong, and is calculated to afford considerable amusement to a child.

Having described my invention, what I 20 claim and desire to secure by Letters Patent is:

1. A wheeled toy comprising a rolling 20 ground member having a bore, and a wire frame, formed of one continuous piece of wire and having a journal portion disposed in said bore and a handle portion disposed at right angles to the journal portion and 25 also having bail arms one of which is joined through a right angle bend to the handle portion and the other of which merges into a support that is disposed in said right-angle bend.
2. A wheeled toy comprising a rolling 30 ground member having a bore, a rectangular frame formed from a single length of wire bent into shape and including a journal portion disposed within said bore, bail 35 arms and a handle portion, one of said bail arms merging into said handle portion by a partial loop and the other bail arm engaging by a right angle bend within said loop and terminating in an upwardly directed 40 support.
3. A wheeled toy comprising a rolling 45 ground member having a bore, a rectangular frame formed from a single length of wire having one portion engaging revolu-

tion provided with a handle, an upwardly directed curved arm formed upon one end of said wire and located at the center of said second named portion, and a body carried by said arm.

4. A wheeled toy comprising a rolling 5 ground member having a transverse bore, a one-piece wire frame having a journal disposed in the bore of the rolling member, a forwardly directed handle portion, 10 and a rearwardly directed support, a platform secured on the frame and receiving said support, and a body secured upon and carried by said support.

5. A wheeled toy comprising a rolling 60 ground member having a bore, a rectangular frame formed from a single length of wire having one portion engaging revolu- 65 bly within said bore and its opposite portion provided with a handle, an upwardly directed curved arm formed upon one end of said wire and located at the center of said second named portion, a body carried by said arm, and a sheet metal platform secured upon said frame and having a hole 70 for the passage of said arm.

6. A wheeled toy comprising a rolling 75 ground member having a bore and a transversely grooved periphery, a frame formed from a single length of wire having a journal portion engaging within said bore and a handle portion, an upwardly extending curved arm formed at one end of said wire, a body carried by said arm, and a platform secured upon said frame and having a hole 80 for the passage of said arm, the end of said platform adjacent said ground member being formed as a resilient tongue engaging the periphery of the ground member.

In testimony whereof I affix my signature in presence of two witnesses.

CHARLES L. WECHT.
